UNITED STATES PATENT OFFICE.

JOHN W. GOULD, OF ELMIRA, NEW YORK.

RAILWAY-CHAIR.

Specification of Letters Patent No. 22,797, dated February 1, 1859.

To all whom it may concern:

Be it known that I, J. W. GOULD, of Elmira, in the county of Chemung and State of New York, have invented a new and Improved Railway-Chair; and I do hereby declare that the following is a full and exact description thereof, reference being had to the accompanying drawings, making part of this specification, Figure 1 being a plan 10 of one of the railway-chairs and the adjacent ends of two rails united thereby; Fig. 2, a section of the chair in the plane indicated by the line $\alpha\alpha$, Fig. 1, exhibiting the mode of inserting the "lock-wedge"; Fig. 15 3, a corresponding section, showing the chair completely arranged for use; Fig. 4, a plan of the "lock-wedge" detached.

Like letters designate corresponding parts in all the figures.

20 My improved railway chair is applicable either as a chair proper, resting on the cross-tie as shown in the drawings; or as a "splice" uniting the ends of the rails, between the cross-ties or sleepers; in which 25 case the "lock-wedge" C, acts as a "fish-piece."

The chair-seat B, is made substantially of the form exhibited in the drawings, so that the bottom and inner side of each rail 30 will fit accurately therein; and between its outer side and the rails there will be a doubly-rounded space, sufficient to receive the "lock-wedge" C, and a key D. Outward from, and just above the outer flange 35 of the rails, is also a notch d , in the chair-seat, as shown, for the reception of the lower edge a , of the "lock-wedge". This edge forms the back of a notch or recess in the "lock-wedge", leaving, at the ends, abrupt 40 shoulders b , b , that, when the "lock-wedge" is entirely inserted, embrace the chair-seat B, and thereby prevent the removal or accidental detachment of the "lock-wedge", which is inserted edge-wise, as indicated in 45 Fig. 2, and has a concavo-convex shape, in

cross section, the convex side fitting into the hollow of the rails, as seen in Fig. 3. The concave side, together with the hollow f , in the chair-seat, offer a rounded aperture, between, into which a key D, is finally 50 driven, for completely tightening the rails in the chair. But should this key work loose, or out of its place, still the "lock-wedge", (which securely remains in place, under all circumstances,) would hold the 55 rails safely, since the back g , of its upper edge, bears firmly against the shoulder h , of the chair-seat.

The "lock-wedge" extends a considerable length along the sides of the rails, and 60 serves to give a uniformity of spring to the entire length of the rails, a result very desirable to be attained. At the same time, the ends are sloped downward below the top of the rails, so as not to allow the car-wheels to strike them.

If the "lock-wedge" is not raised flush with the tops of the rails, although it does not take the tread of the wheels, yet its use and utility in all other respects, remain 70 as above set forth.

The "lock-wedge" can only be removed by raising it edgewise upward out of the chair seat.

I am aware that side pieces or rails have 75 been applied at the joints of the rails, to take the tread of the car-wheels; therefore I do not claim that device.

What I claim as my invention and desire to secure by Letters Patent, is—

The self-securing "lock-wedge" C, arranged in combination with the rails A, A, chair-seat B, and key D, substantially in the manner and for the purpose herein specified.

JOHN W. GOULD.
